SHOE MACHINE

Charles A. Robinson, Salem, Mass., assignor to
United Shoe Machinery Corporation, Flemington, N. J., a corporation of New Jersey

Application May 20, 1943, Serial No. 487,711

10 Claims. (Cl. 12—51)

This invention relates to machines for operating upon shoes and particularly to a machine for preparing Goodyear welt shoes for the inseam sewing operation by shaping the upper materials in those portions of the shoe adjacent to the ends of the inseam.

In the manufacture of Goodyear welt shoes, after the shoe has been toe and side lasted and the heel-seat lasted and tacked, there is usually to be found in the overlasted margin of the upper adjacent to the breastline a bulge or lump caused by the bowing out of the stiff counter material or its bridging and failure to conform accurately and closely to the face of the feather and outside of the rib of the insole. This bulge or lump comes substantially at the points where the inseam should begin, and end, and this irregularity in the contour of the overlasted upper makes it difficult for the operator of the welt sewing machine to position the shoe so that the needle will strike exactly at the base of the insole rib and in the angle between the feather and the rib. Instead, the needle is more likely to engage the upper material at a point away from this angle, making a wide stitch which is detrimental to fine shoemaking. It has been the practice for the shoemaker to shape the shoe at these points by pounding with a hammer to bring the upper materials down onto the feather and in against the rib, but this requires considerable labor, time and skill and is likely to be neglected or imperfectly done. Various types of power-operated machines for shaping the upper materials adjacent to the breastline by means of pressure, percussive action or rubbing have also been proposed.

A principal object of this invention is to provide a novel and improved machine for shaping the upper materials on the opposite sides of a Goodyear welt shoe, adjacent to the breastline, by means of a heated ironing and pressing tool which is simple in construction, easy to operate, and very effective in its action. To this end, and in accordance with a feature of this invention, the machine is provided with a rapidly reciprocating tool which is movable to and from an operative position together with supporting means for locating a shoe in position for the upper materials at one side thereof and adjacent to the breastline to be engaged by the tool as it is moved to operative position. Preferably, and as shown, the shoe-supporting means comprises a member for engaging the inside angle of the insole rib of a shoe, held bottom up in the hands of the operator, to hold the shoe against widthwise movement by the tool, the member being arranged so

5 to position the shoe that the advancing tool will strike the upper materials just below the point where they start to curve abruptly inward over the edge of the insole. The supporting means is yieldably mounted so that it can follow the shoe when the shoe moves downwardly, as permitted by the operator, during the continued advance of the tool. In this way the upper materials are wiped in over the feather and tightened on the 10 side of the last, by the advancing tool, so that wrinkling, or loosening, thereof at the side of the shoe is avoided. The supporting means also has a surface which bears against the inside of the rib to prevent it from being bent over by the 15 pressure of the tool in pressing the upper materials against its outside face and a narrow edge which forms a well-defined crease at the inside angle of the rib. As the tool advances in over the bottom of the shoe, the upper materials are 20 ironed down onto the feather and eventually creased in against the rib, the effect of the heated tool greatly facilitating this action and tending to set the upper in place.

The above and other objects and features of 25 this invention will appear in the following detailed description of the preferred embodiment thereof, shown in the accompanying drawings, and will be pointed out in the claims.

In the drawings, 30 Fig. 1 is a view in side elevation of a machine embodying this invention;

Fig. 2 is a view, also in side elevation and at an enlarged scale, of the operating parts of the machine shown in Fig. 1;

Fig. 3 is a plan view of these parts; and

Fig. 4 is a sectional view taken on line IV—IV of Fig. 2, looking in direction of arrows.

The illustrated machine comprises a head 10 which may be supported in any suitable manner, 40 as by a pedestal, not shown, and at a height convenient for the operator. This head has a forwardly extending arm 12 which carries an ironing tool 14 and also a work support 16. The ironing tool is formed integrally with an arm 18, 45 which is pivotally mounted on a stud 20 carried by a block 22, and at its forward end has a rearwardly inclined and somewhat rounded face 24, providing a blunt, chisel-like, working edge 26. This edge is rounded off at its opposite ends and the bottom surface 28 of the tool is slightly convex (Figs. 2, 3 and 4).

The arm is oscillated rapidly, to reciprocate the tool in a direction generally lengthwise of a shoe being operated upon, by means of an eccentric 55 on the end of a shaft 32. This eccentric is re-

tatably mounted in a block 34 that is slidable in a slot 36 in the arm 18, Fig. 3. This block extends below the arm where it is provided with extended portions 38 and 40. A thrust washer 42 secured to the shaft holds the parts in operative positions with the upper and lower surfaces of the arm in free sliding engagement with the block portions 38 and 40 and a finished boss 44 on the arm 12 from which the shaft extends. A pulley 46, secured to the shaft by means of a taper pin 48, bears against another finished boss 50 and thus prevents downward movement of this shaft and the arm 18. This pulley is driven by a belt 52 which extends rearwardly over idlers 54, one of which is shown in Fig. 1, and downwardly to a suitable source of power (not shown).

The block 22 is T-shaped and is slidably mounted in a T-shaped guide 60 which extends forwardly from the head 10. This block is also hollowed out at 62 to receive a trunnion pin 64 and trunnion block 66 which is embraced by the forked end 68 of one arm 70 of a bell-crank lever extending upwardly through an opening 72 in the bottom of the guide. This bell-crank lever is pivotally mounted on the head by means of a shaft 74 and its other arm 76 carries a treadle rod 78. The opening 72 terminates at each end in surfaces 80 and 82 which cooperate with stop surfaces 84 and 86 on the arm 70 to limit swinging movement of this arm, and likewise sliding movement of the block 22, in opposite directions. Normally these parts are held to the left, and the tool 14 in an inoperative position away from the work, Fig. 1, by means of a tension spring 88 which is secured at one end to the arm 76 and at its other end to a pin 100 extending from the front end of the guide 60.

The work support 16 has a beveled front face 102 and is mounted on a supporting block 104 which is secured to the arm 12 by means of a screw 106. This screw passes through a slot 108 in an extended portion of the block which permits heightwise adjustment of the work support relative to the tool 14. The work support is pivoted to the block by means of a pin 110 and has an end portion 114 which is engaged by a spring 112. This spring, the tension of which may be varied by means of a screw plug 118, normally holds the work support in the position shown in Fig. 1, with its upper side against the bottom face 116 of a groove in the block 104.

The tool 14 is heated by means of an electric heating unit 120 from which lead wires 122 extend back to a control box 124. Within this box is a switch, operated by a tumbler 126, and a thermostatic cutout which may be set for the desired tool temperature by means of a knob 128.

The machine operates in the following manner: After starting the machine, the operator grasps a shoe S, comprising an upper U, an insole I, a counter stiffener C and a lining L, which previously has been lasted along the sides and around the heel end, and presents it bottom upward against the support 16 with the bottom face of the insole in a substantially horizontal plane and with the narrow edge of the support engaging the insole in the angle formed by the inside face of a rib R on the insole and the bottom face of the insole. It will be understood that the shoe is thus positioned with the support 16 in the locality where it is desired to iron-in the upper materials. The tool 14 is at this time in its inoperative position, i. e., spaced a short distance widthwise from the shoe, and is being rapidly reciprocated lengthwise of the shoe. The adjusted position of the block 104 on the arm 12 is prefer-

ably such that with the shoe presented as above described in engagement with the support 16 the bottom face 28 of the tool is just a little below a horizontal plane passing through the feather F of the insole I. The tool is now moved inwardly toward the shoe by means of the treadle rod 78, bell crank 76 and block 22, and strikes the shoe at just about the point where the upper materials start to lay in over the shoe bottom. Upon continued movement of the tool the shoe is pressed downwardly, the support 16 following this downward movement by pivoting about the pin 110, against the action of the spring 112 and the resistance set up by the operator, and the upper materials are wiped in over the feather. Ultimately the tool reaches the position shown in Fig. 2 where it irons the upper materials down onto the feather F of the insole and into the angle between the feather and rib R which is supported by the front face 102 of the support 16. During this action the operator may swing the shoe, about 16 as a pivot, to accommodate the particular condition of the upper materials and slope of the feather and he can also, after the tool has reached its limit of inward movement, press the shoe up against the tool to enhance the ironing action. The zone of operation of the working face of the tool is great enough to cover all of that part of the upper materials on one side of a shoe which need to be shaped in the ordinary run of shoes. However, the shoe can be shifted lengthwise by the operator, if desired, to bring other portions of the upper materials into engagement with the tool.

The heated tool sets the upper materials into the position shown in Fig. 2 and eliminates the bulging or bridging of the upper materials, which is almost always present adjacent to the breast insole. A comparison of Fig. 1, in which the bridging is evidenced by the space B, with Fig. 2, in which this space has been eliminated, will demonstrate the improved condition of the upper which is obtained by the use of this machine. The support 16 engages the insole rib to prevent widthwise movement of the shoe as the tool is advanced, and its narrow edge, which is pressed firmly into the inside angle of the rib by resisting the widthwise thrust of the tool, forms a definite crease for receiving the anvil of the inseaming machine. The advantages of having the upper materials ironed in against the feather and into the angle of the rib at the breast line from the standpoint of starting and finishing the inseaming operation have been pointed out above and will be apparent to those skilled in the art. This ironing operation can be done in a very short time with this machine and, when the operator has the shoe in his hand, he can conveniently smooth up other parts of the shoe by using either the bottom or front rounded faces 28 or 24 of the tool.

Having described my invention, what I claim as new and desire to secure by Letters Patent of the United States is:

1. A machine for shaping the upper materials of a lasted shoe comprising a tool for forcing the upper materials down onto a feather and in against a rib on the insole of the shoe, means for engaging the bottom of a shoe to locate the shoe in proper heightwise relation to the tool, means for rapidly and continuously reciprocating the tool in a direction extending generally lengthwise of the shoe, and means for advancing the reciprocating tool into operative engagement with the upper materials.

2. A machine for shaping the upper materials of a lasted shoe comprising a heated tool for forcing the upper materials down onto a feather and in against a rib on the insole of the shoe, means for engaging the bottom of a shoe to locate the shoe in proper heightwise relation to the tool, means for rapidly and continuously reciprocating the tool in a direction extending generally lengthwise of the shoe, and means for advancing the reciprocating tool into operative engagement with the upper materials.

3. A machine for shaping the upper materials of a lasted shoe comprising an ironing tool for forcing the upper materials down onto a feather and in against a rib on the insole of the shoe, said tool being arranged for movement to and from an operative position, means for engaging the bottom of a shoe, held by an operator, to locate the shoe heightwise so that the point where the upper curves inwardly over the bottom of the shoe is substantially in line with the tool, means for rapidly and continuously reciprocating the tool in a direction extending generally lengthwise of the shoe, and means for advancing the reciprocating tool into operative engagement with the upper materials.

4. A machine for shaping the upper materials of a lasted shoe comprising a reciprocating ironing tool for forcing the upper materials down onto a feather and in against a rib on the insole of the shoe, said tool being arranged for movement to and from an operative position, means for engaging the bottom of a shoe, held in the hands of an operator, to locate the shoe heightwise so that the tool, when it is advanced, will engage the upper materials at the point where the upper starts to curve abruptly inwardly over the shoe bottom and move the shoe downwardly, said shoe-engaging means being yieldable in one direction so as to follow the shoe in its downward movement as the tool is advanced, and means for advancing the tool into operative engagement with the upper materials.

5. A machine for shaping the upper materials of a lasted shoe comprising an ironing tool having a blunt, chisel-like operating edge for shaping the upper into the angle between a feather and a rib on the insole of the shoe and an ironing surface for pressing the upper materials down onto the feather, means for engaging the bottom of the shoe to locate the shoe in proper heightwise relation to the tool, means for rapidly and continuously reciprocating the tool in a direction extending generally lengthwise of the shoe, and means for advancing the reciprocating tool into operative engagement with the upper materials of a shoe.

6. A machine for shaping the upper materials of a lasted shoe comprising an ironing tool for forcing the upper materials down onto a feather and in against a rib on the insole of the shoe, supporting means for engaging the bottom of the shoe in the inside angle between the feather and the rib to locate the shoe heightwise of the tool and to hold it against widthwise movement by the tool, means for rapidly and continuously reciprocating the tool in a direction extending generally lengthwise of the shoe, and means for advancing the reciprocating tool into operative engagement with the upper materials of a shoe held against said supporting means.

7. A machine for shaping the upper materials of a lasted shoe comprising a reciprocating ironing tool for forcing the upper materials down onto a feather and in against a rib on the insole of the shoe, said tool being arranged to be advanced to an operative position, supporting means for engaging the bottom of a shoe in the inside angle or the rib to locate the shoe heightwise so that the tool, when it is advanced, will engage the upper materials where they start to curve abruptly inwardly over the shoe bottom and move the shoe downwardly, said supporting means being yieldable in one direction so as to follow heightwise movement of the shoe as the tool is advanced, and means for advancing the tool into operative engagement with the upper materials.

8. A machine for shaping the upper materials of a lasted shoe comprising a reciprocating ironing tool for forcing the upper materials down onto a feather and in against a rib on the insole of the shoe, said tool being arranged to be advanced from an inoperative to an operative position, supporting means for engaging the bottom of a shoe in the inside angle of the rib to hold the shoe against widthwise movement by the tool and to locate the shoe heightwise so that the tool, when it is advanced, will engage the upper materials where they start to curve abruptly inwardly over the shoe bottom, said supporting means being yieldable to follow heightwise movement of the shoe as the tool is advanced, and means for advancing the tool into operative engagement with the upper materials.

9. A machine for shaping the upper materials of a lasted shoe comprising a reciprocating ironing tool arranged for movement from an inoperative to an operative position and having a blunt, chisel-like operating edge for shaping the upper materials into the angle between a feather and a rib on the insole of the shoe and an ironing surface for pressing the upper materials down onto the feather, supporting means for engaging the bottom of the shoe in the inside angle of the rib to hold it against widthwise movement by the tool and to locate the shoe heightwise so that the tool, when it is advanced, will engage the upper materials where they start to curve abruptly inwardly over the shoe bottom, said supporting means being yieldable to follow heightwise movement of the shoe as the tool is advanced, and means for advancing the tool into operative engagement with the upper materials.

10. A machine for shaping the upper materials of a lasted welt shoe comprising a lasting tool for forcing the upper materials down onto a feather and in against a rib on the insole of the shoe, said tool being arranged to be advanced from an inoperative to an operative position, supporting means for engaging the bottom of a shoe in the inside angle of the rib to locate the shoe heightwise with respect to the tool and to hold it against widthwise movement by the tool, said supporting means having a face for engaging the inside of the rib to prevent distortion of the rib by the tool as it is advanced, means for rapidly and continuously reciprocating the tool in a direction extending generally lengthwise of the shoe, and means for advancing the reciprocating tool into operative engagement with the upper materials.

CHARLES A. ROBINSON.
